UNITED STATES PATENT OFFICE.

FELIX O'DONNELL, OF PAWTUCKET, RHODE ISLAND, ASSIGNOR OF ONE-HALF TO SUSAN A. BROWN, OF PAWTUCKET, RHODE ISLAND.

WEFT-REPLENISHING MECHANISM FOR LOOMS.

SPECIFICATION forming part of Letters Patent No. 767,426, dated August 16, 1904.

Application filed April 28, 1903. Serial No. 154,708. (No model.)

To all whom it may concern:

Be it known that I, FELIX O'DONNELL, a resident of the city of Pawtucket, in the county of Providence and State of Rhode Island, have invented certain new and useful Improvements in Weft-Replenishing Mechanism for Looms; and I do hereby declare that the following is a full, clear, and exact description thereof, reference being had to the accompanying drawings, and to the letters of reference marked thereon, which form a part of this specification.

This invention relates to weft-replenishing mechanism for looms, the object of which is to instantly arrest the feed or forward movement of the woven cloth when the weft-thread breaks or runs out of the shuttle and at the same time to cause the replenishing mechanism to be operated and drive a full cop or bobbin into the shuttle.

By the use of this device the cloth-take-up roll ceases to operate if for any cause the weft-fork fails to find the weft-thread when the lay beats up and the take-up roll remains at rest until the shuttle has been replenished and is again laying the filling correctly into the goods. Then the take-up roll is automatically set in motion and the loom proceeds to weave as before the break. This method of stopping the take-up roll effectually prevents the weaving of thin places in the cloth.

This invention is fully set forth in this specification and illustrated in the accompanying drawings.

Figure 1 is an end elevation of the loom, showing my mechanism attached thereto. Fig. 2 is an end elevation of the loom, showing my connection between the weft-fork-operated rod *r* and the weft-replenishing mechanism. Fig. 3 is a sectional side elevation showing the cloth-take-up mechanism and my method of operating the feed-controlling pawl on the ratchet-wheel *G*. Fig. 4 is a perspective view showing the connection between the weft-fork and the pawl which controls the feed of the cloth-take-up roll.

Referring to the drawings, *A* is the loom-frame, and *B* the breast-beam, fixed thereon.

C is the cloth-take-up roll, (see Fig. 3.)

which is driven in the manner well known to those skilled in the art through the sand-roll *D*, gear *E*, pinion *F*, and ratchet-wheel *G*, all of which are actuated by the engagement of the driving-pawl *i* with the ratchet-wheel *G*. This pawl is operated to move vertically by its connection with the lever *V*, which lever is raised and lowered by the rotating cam *S* on the cam-shaft *J*. This ratchet-wheel *G* moves back and forth with the reciprocating pawl unless prevented from its backward movement by the engagement of pawl *H* with the teeth of the wheel to hold it still while pawl *i* goes down for another tooth, by which the wheel is fed ahead on the next upstroke of this pawl *i*. The pawl *H* is pivoted to the frame at *I* and has an upwardly-extending arm *m* with which my new device comes in contact to raise the pawl. The guide-plate *d* is secured to the top of the breast-beam between the woven cloth and the end frame. A plate *d'* is fitted to slide in the recess in said guide-plate, or a recess may be made in the top of the breast-beam for the plate *d'* to slide in. A weft-fork *h* is held on a pin in the inner end of the sliding plate *d'*, so that the weft-thread *a* on the lay from the shuttle to the cloth will come in contact with the lower part *c* of the fork and tip the back end up when the lay comes forward to beat up the filling. A lever *V* is pivoted at one end to the frame on a stud *t*, with its free end resting on the cam *S*. This lever *V* has an arm *v* extending up with its upper end in the recess of the sliding plate *d'* in position to strike against the projection *h'* on the end of the weft-fork lever *h* when it is not raised out of the path of this reciprocating lever by the fork catching against the weft-thread *a* as the lay comes forward. The outer end of this sliding plate *d'* is grooved transversely at *e* to receive one end of the dog *R*, which is fixed to the shaft *r*, which shaft is caused to turn or rotate as the fork-plate *d'* is moved back or forth by the lever-arm *v*. A dog *R'* is also fixed to this shaft *r* near its end, the lower end of which engages the upwardly-extending arm *m* of the pawl *H*, by the movement of which dog said pawl is actuated and held out of engagement with the ratchet-

wheel G when the weft-fork fails to engage a weft-thread, thereby instantly arresting the feed of the take-up roll and warp let-off. The lever K is for the purpose of being operated by the swell-actuating mechanism to throw off the starting-lever L, as is well known, and in the ordinary loom it is also arranged to be operated by the movement of the weft-fork; but when my cloth-take-up stop-motion is used in combination with the weft-replenishing mechanism I prefer to arrange this lever K so it will not be operated by the weft-fork, as I do not wish to stop the loom, but only desire to stop the forward movement of the goods when the weft-thread runs out and at the same time operate the replenishing mechanism to drive a full cop or bobbin into the shuttle. To allow this fork-plate d' to reciprocate in the guide plate d and be held in place by and without acting on the lever, I cut a groove transversely through both of said fork and guide plates and insert a finger K', which projects from the end of the shipper-lever K and lies across this guide-plate and holds the fork-plate from coming out.

The weft-fork is operatively connected with the weft-replenishing-actuating mechanism through the shaft r, to which shaft the dog R is connected from the fork-plate d'. This shaft runs across the front of the machine (see Fig. 1) under the breast-beam to the end of the loom on which the replenishing mechanism is located. The arm w is fixed to the outer end of this shaft and has a roll in its lower end which engages the inclined end of the lever T. This lever is pivoted near its center at n and is connected at its inner end to rod y, which acts to raise the lever g' out of engagement with the plate e' and actuates the replenishing mechanism in the manner illustrated and described in my patent issued March 18, 1902, No. 695,696. The balance weight r' is hung on shaft r (see Fig. 3) and is for the purpose of returning the weft-fork and the rest of the mechanism hung on said shaft to its normal or rest position after having been thrown out by lever v.

The operation of my invention is further explained as follows: By my method of connecting the weft-fork plate d' to the cloth-take-up-actuating mechanism as above described the weaving of thin places in the goods is effectually prevented. My device for accomplishing this is extremely simple and effective in its construction and operation and has proved itself very effective when used in connection with this type of weft-replenishing type of loom, as it allows the loom to continue running while the shuttle is being replenished, but stops the goods from feeding ahead until the shuttle is again laying the filling into the web correctly, when the cloth automatically starts feeding ahead again.

Having thus described my invention, what

I claim as new, and desire to secure by Letters Patent, is—

1. In a weft-replenishing mechanism for looms including a cloth-take-up roll, a ratchet-wheel, a detent-pawl for engaging said ratchet-wheel, a shipper-lever, a weft-fork, a weft-fork slide, a guide-plate, said plate and said slide being cut away or recessed transversely to receive the end of said shipper-lever, a shaft, a dog fixed to said shaft operated by the movement of the weft-fork slide to rotate said shaft, a second dog mounted on said shaft for engaging the upper end of said detent-pawl, a lever connected to the weft-replenishing mechanism and an arm mounted on said shaft engaging said lever by which the weft-replenishing mechanism is actuated to replenish the shuttle. 75 75

2. In a weft-replenishing mechanism for looms including a cloth-take-up roll, a ratchet-wheel, a detent-pawl for engaging said ratchet-wheel, a shipper-lever, a weft-fork, a weft-fork slide, a guide-plate, said plate and said slide being cut away or recessed transversely to receive the end of said shipper-lever, a shaft, a dog fixed to said shaft operated by the movement of the weft-fork slide to rotate said shaft, a second dog mounted on said shaft for engaging the upper end of said detent-pawl, a lever connected to the weft-replenishing mechanism, and an arm mounted on said shaft engaging said lever by which the weft-replenishing mechanism is actuated to replenish the shuttle, substantially as described. 80 85 90

3. In a weft-replenishing mechanism for looms, including a cloth-take-up roll, a ratchet-wheel, a detent-pawl, said detent-pawl to engage said ratchet-wheel, a weft-fork, a weft-fork slide, a shaft hung longitudinally under the breast-beam, a dog fixed to said shaft, operated by the movement of the weft-fork slide to rotate said shaft, a second dog mounted on said shaft for engaging the upper end of said detent-pawl, a lever connected to the weft-replenishing mechanism, and an arm mounted on said shaft engaging said lever by which the weft-replenishing mechanism is actuated to replenish the shuttle, substantially as described. 95 100 105

4. In a weft-replenishing mechanism for looms including a cloth-take-up roll, a ratchet-wheel, a detent-pawl, said detent-pawl to engage said ratchet-wheel, a shipper-lever, a weft-fork, a weft-fork slide, a guide-plate, said plate and said slide being cut away or recessed transversely to receive the end of said shipper-lever, a shaft hung longitudinally under the breast-beam, a dog fixed to said shaft operated by the movement of the weft-fork slide to rotate said shaft, a second dog mounted on said shaft for engaging the upper end of 110 115 120 125 130

5 said detent-pawl, and an arm mounted on said shaft, a lever pivoted on the loom-frame, one end of said lever operatively connected to the detent-pawl on the weft-replenishing mechanism the opposite end of said lever engaging said arm, by which said lever is actuated when the weft-fork fails to find the weft-thread, substantially as described.

10 5. In a weft-replenishing mechanism for looms, including a cloth-take-up roll, a ratchet-wheel, a detent-pawl for engaging said ratchet-wheel, a shipper-lever, a weft-fork, a weft-fork slide, a guide-plate, said plate and said slide being cut away or grooved transversely 15 to receive the end of said shipper-lever, a shaft hung longitudinally under the breast-beam, a dog fixed to said shaft operated by the movement of the weft-fork slide to rotate said shaft, a second dog mounted on said shaft for engaging the upper end of said detent-pawl, a weight hung on said shaft to automatically return the fork-plate to its normal position, and means connected to said shaft for actuating the weft-replenishing mechanism when the 25 weft-fork fails to engage a weft-thread, substantially as described.

6. In a weft-replenishing mechanism for looms including a cloth-take-up roll, a ratchet-wheel, a detent-pawl, said detent-pawl to engage said ratchet-wheel, a weft-fork, a weft-fork slide, a shaft hung longitudinally under the breast-beam, a dog fixed to said shaft operated by the movement of the weft-fork slide to rotate said shaft, a dog mounted on said 35 shaft for engaging the upper end of said detent-pawl, an arm mounted on said shaft, and a lever pivoted on the loom-frame, one end of

40 said lever operatively connected to the detent-pawl on the weft-replenishing mechanism, the opposite end of said lever being provided with an inclined portion, the lower end of said arm engaging said inclined portion of said lever by the movement of which arm said lever is actuated to raise said weft-detent pawl and allow the weft-replenishing mechanism to be 45 actuated, substantially as described.

7. In a weft-replenishing mechanism for looms, a cloth-take-up roll, a ratchet-wheel, a detent-pawl, said detent-pawl to engage the ratchet-wheel, a weft-fork, a weft-fork slide, 50 a shaft hung longitudinally under the breast-beam, a dog fixed to said shaft operated by the movement of the weft-fork slide to rotate said shaft, a second dog mounted on said shaft for engaging the upper end of said detent-pawl, a weight hung on said shaft for automatically returning the fork-plate to its normal position, an arm mounted on said shaft, a lever pivoted on the frame, one end of said lever operatively connected to the detent-pawl on the weft-replenishing mechanism, the opposite end of said lever being provided with 55 an inclined portion, the lower end of said arm engaging said inclined portion of said lever by the movement of which arm said lever is actuated to raise said weft-detent pawl and allow the weft-replenishing mechanism to be 60 actuated, substantially as described.

In testimony whereof I have hereunto set my hand this 27th day of April, A. D. 1903. 70

FELIX O'DONNELL.

In presence of—

HOWARD E. BARLOW,
CHAS. P. DAY.
